Primary Examiner — Philip S Hyder(74) Attorney, Agent, or Firm — Bell Nunnally & Martin LLP(57) CLAIM

The ornamental design for a buckle release, as shown and described.

DESCRIPTION

FIG. 1 is a perspective view of a buckle release in accordance with our design;

FIG. 2 is a right side view thereof;

FIG. 3 is a left side view thereof;

FIG. 4 is a top plan view thereof;

FIG. 5 is a bottom plan view thereof;

FIG. 6 is a back view thereof; and,

FIG. 7 is a front view thereof.

The broken lines shown in the drawings illustrate portions of the buckle release in which the design is embodied that form no part of claimed design.
